UNITED STATES PATENT OFFICE.

OTIS A. MYGATT, OF NEW YORK, N. Y.

DESIGN FOR A REFLECTOR FOR INCANDESCENT ELECTRIC LAMPS.

No. 37,835.

Specification for Design.

Patented Feb. 20, 1906.

Application filed August 1, 1905. Serial No. 272,264. Term of patent 14 years.

To all whom it may concern:

Be it known that I, OTIS A. MYGATT, a citizen of the United States, residing at New York, in the county of New York and State of New York, have invented a certain new, original, and ornamental Design for Reflectors for Incandescent Electric Lamps, of which the following is a specification, reference being had therein to the accompanying drawings, forming part thereof.

Figure 1 is a side elevation of a reflector embodying the form or configuration of my

design. Fig. 2 is a perspective view as seen from above the plane of the reflector. Fig. 3 is a perspective view as seen from below the plane of the reflector.

I claim—

The ornamental design for a reflector for incandescent electric lamps, as shown.

OTIS A. MYGATT.
